ATTORNEY

UNITED STATES PATENT OFFICE.

HERBERT L. STULL, OF SEATTLE, WASHINGTON.

FOLDING CHAIR.

1,126,911.

Specification of Letters Patent.

Patented Feb. 2, 1915.

Application filed June 18, 1913. Serial No. 774,331.

To all whom it may concern:

Be it known that I, HERBERT L. STULL, citizen of the United States, residing at Seattle, in the county of King and State of Washington, have invented a certain new and useful Improvement in Folding Chairs, of which the following is a specification.

My invention relates to improvements in folding chairs and the object of my improvement is to provide a folding chair that may be placed on the seat of an ordinary chair to serve as a high chair for children. I accomplish this object by devices illustrated in the accompanying drawings, wherein—

Figure 1, is a view in side elevation of a structure embodying my invention as it appears when placed on an ordinary chair in readiness for use; Fig. 2 is a view in front elevation of the same; Fig. 3, is an enlarged sectional view on broken line α , α of Fig. 2, showing the bottom of the folding chair seat; Fig. 4, is a plan view of the food tray and its associated parts; and Fig. 5, is an enlarged fragmentary view of a detail of my invention.

Like reference numerals indicate like parts throughout the several views.

Referring to the accompanying drawings, wherein I have illustrated a practical embodiment of my invention, 6 is the seat of a child's folding chair that is adapted to be supported at a suitable distance above the seat of an ordinary dining room chair 7, by forward legs 8, 8 and rearward legs 9, 9. The child's folding chair is provided with a hinged back 10 and with hinged right and left side arms 11 and 12 respectively.

The front legs 8, 8 herein illustrated as made of a single piece of material, have their upper ends formed in the shape of a letter L and are pivotally secured to the under side of the chair seat 6, by clips 13 in such manner that they may be folded inwardly against said chair seat or may be turned to project vertically downward as illustrated in Figs. 1 and 2, the L shaped upper end serving as a stop to prevent the legs 8, 8 from swinging forward and slipping off the chair. The back legs 9, 9 are each pivotally secured to downwardly projecting ends of an L shaped bracket 14, by rivets 15, and are prevented from swinging backwardly by lugs 16 which serve to engage the brackets 14 as illustrated in Fig. 5. The bracket 14 is slidably mounted in guides 17, secured to the lowermost surface of the

chair seat 6 as illustrated in Fig. 3, through which guides it may be moved to provide means for adjusting the back legs 9, 9 of the folding chair to fit the dining room chair 6 of different sizes. Two helical tension springs 18 and 19 each having one of its ends attached to the bracket 14 and the other of its ends attached to the cross-rod of the legs 8, 8 or other fixed portion of the 69 chair seat 6 serve always to keep the back legs 9, 9 drawn forward and to prevent them from slipping backwardly over the edge of the chair 7.

Each of the legs 8, 8 and 9, 9 is provided 70 with an offset near its bottom, which offset is adapted to extend over and engage the edge of the chair 7, and padding 20 as rubber, felt or the like, is disposed on the offset portion of the leg in such manner that it 75 shall be interposed between said leg and the seat of the chair 7 to prevent marring or scratching the chair 7 when the child's folding chair is placed thereon.

The side arms 11 and 12 and the back 10 80 are pivotally mounted on the top surface of the seat 6 adjacent its two lateral edges and its back edge respectively in a manner similar to the manner in which the forward legs 8, 8 are mounted on the under surface of 85 said seat 6 and are similarly formed to prevent said side arms and back from swinging outwardly further than may be desired.

A cross-bar 21 having a food tray 22 secured thereto has one of its ends pivotally 90 connected with one member of a hinge 23 by a rivet 24, and the other member of the hinge 23 being secured to the forward end of the left chair arm 11, as illustrated in Fig. 4. The opposite end of the bar 21 is 95 provided with a downwardly projecting pin 25 which has an enlarged portion or knob 26 at its lower end and is adapted to have said knob 26 thrust downwardly through an enlargement 27 in a slotted hole 28 provided 100 near the forward end of the right hand chair arm 12 and to be moved forward in said slotted hole 28 until the enlarged portion 26 shall engage the bottom edges of said slotted hole 28 to secure the bar 21 to 105 the right hand side arm 12.

When in use the child's folding chair may be disposed on any ordinary chair 7, as illustrated in Figs. 1 and 2, the back legs being adjustable so that it may be made to 110 fit ordinary chairs of varying size. If it be desired to fold the chair the pin 25 may be

moved backwardly in the slotted hole 28 until the knob 26 may be withdrawn through the enlarged portion 27 of the slotted hole 28. The cross-bar 21 may then be raised to a vertical position to permit a child easily to be removed from the chair. The top of the cross-bar 21 may then be moved backwardly, the bar 21 turning on the rivet 24, to permit the cross-bar 21 and tray 22 to be 10 folded downwardly beside the left chair arm 11. The arm 11, the bar 21, and the tray 22 may then be folded downwardly on the top surface of the chair seat 6, the right chair arm 12 may be folded downwardly on 15 the top of the left chair arm 11 and the back 10 folded downwardly on the whole. The child's chair may then be removed from the chair 7, the legs folded upwardly against the lower surface of the seat 6 thus making 20 a compact article which may be stored in a small space.

In the construction of my chair the pivot joints of the legs, arms and back respectively, preferably may be made to fit tightly 25 in order that these hinged members may remain folded without providing catches, hooks or the like, to retain them in their folded positions.

Manifestly my folding chair may be made

of any desired size or shape and various 30 changes in the construction thereof may be resorted to without departing from the spirit of my invention or sacrificing any of its advantages.

What I claim is:

The combination with the seat of a small chair that is adapted for attachment to a larger chair, of a U-shaped bracket slidably secured to the under side of said small chair seat, rear legs depending from said bracket, 40 a pair of front legs pivotally secured to the under side of said small chair seat and connected by a cross-bar disposed parallel to the front bar of said bracket, each of said legs being provided on its lower end portion with an offset adapted to engage the edge portions of the seat of said larger chair, and a spring connection between said bracket and the cross-bar of said front legs, whereby the offset portions of said legs may 45 be adjusted to chair seats of different sizes.

In witness whereof, I hereunto subscribe my name this 29th day of May A. D. 1913.

HERBERT L. STULL.
